1

This invention relates to cathode ray apparatus and particularly to systems for deflecting an electron beam of such apparatus.

Cathode ray devices wherein a cathode ray or a beam of electrons is deflected over a target electrode have many uses such as oscilloscopes, television receivers, and in some cases as radiant energy receivers and/or converters. In the latter case it has been proposed to employ a tube of this general character as the sole means for receiving radiant energy at a relatively high carrier frequency and for demodulating this energy, whereby the signal modulating component may be recovered and amplified suitably for impression upon a reproducing device.

Apparatus of this latter type generally comprises an apertured target electrode over which an electron beam is deflected at the received carrier frequency and at an amplitude or deflection magnitude in accordance with the intelligence signal modulated upon the carrier. In one form of such a device, where it is desired to effect demodulation of the received carrier, an electron multiplier is located behind the aperture of the target electrode in a position to receive, at the carrier frequency, a plurality of electronic impulses resulting from the beam deflection over the aperture. For demodulation purposes advantage is taken of the inherent characteristic of an electron multiplier whereby it is incapable of responding to frequencies above a predetermined cutoff frequency. Accordingly, in order for such a device to function as a demodulator it is necessary to effect the deflection of the electron beam over the aperture at a frequency which is greater than the cutoff frequency of the multiplier. If the beam deflection is controlled by the received signal, the carrier frequency of which is greater than the cutoff frequency of the multiplier, it is seen that the required conditions are fulfilled.

However, where a single tube receiver of the character described is to perform satisfactorily under substantially all conditions met in practice, the tube must have a deflection sensitivity of a relatively high order of magnitude. Even in strong signal areas the energy intercepted by a receiving antenna is quite small for use as the deflection voltage for an electron beam. The magnitude of the beam deflection depends upon a number of factors. One factor is the velocity of the beam. A much greater deflection by a given deflection voltage may be effected of a relatively low velocity beam than of one of high velocity. A high velocity beam is one which frequently is

5 termed a "stiff" beam; in other words, one which is not easily diverted from a given path. Hence, in a tube for use as a so-called single tube receiver it is desirable to use a beam of a relatively low velocity. Where this is done the transit time of such a beam becomes relatively great. In such a case, however, it is possible to effect the desired deflection of the beam by a relatively weak field produced under the control of the received carrier frequency signals but one which extends for 10 a considerable distance in the direction of the electron beam travel. In this manner the beam would be subjected to the influence of the deflecting field for a time sufficient to effect the desired deflection thereof.

15 But, where the deflecting field is to be produced under the control of signal voltages of a frequency beyond the cutoff frequency of an electron multiplier, an extensive field of this character 20 would reverse in polarity many times during the transit therethrough by a given portion of the beam by reason of the fact that the frequency of the deflecting voltage is so great in comparison with the electron transit time. Thus, instead of 25 deflecting the beam as desired, its deflection in traveling through such a field would be first in one sense and then in the other, so that upon emerging from the field it might not be deflected 30 at all from its original path. In the most favorable case where the emergence of the beam from the field occurs at a time when the field producing deflection voltage is at a maximum value and corresponds in polarity to the deflection voltage at the beginning of the field traversal by the beam, the resultant beam deflection might still 35 be too small for practical use for the reason that the deflection voltage even at its maximum instantaneous value would necessarily be relatively small. It thus is apparent that, in order to avoid 40 the transit time effects of the electron beam, it is necessary to provide deflection fields of relatively small extent so that the time required for the electron beam to travel through the field will correspond substantially with the time duration 45 of a voltage maximum of the relatively high frequency carrier current signal. But as seen, such a field is in many cases not of sufficient strength to effect the desired deflection of the electron beam.

50 It, therefore, is an object of the present invention to provide a novel deflection system for a cathode ray tube whereby to effect a relatively large beam deflection under the control of relatively small deflection voltages.

In accordance with this invention, there is pro-

vided a source of beam deflection energy and a means including an electrical structure such as a transmission line for producing a time spaced distribution of the deflection energy. Also there is provided a means for utilizing the time distributed energy to produce successively a plurality of beam deflecting fields spaced along the path of the beam.

In a so-called single tube receiver embodiment of the invention, more specifically there is provided a cathode ray tube having a source of an electron beam and, in spaced relation thereto, a target electrode. There also is provided means for producing a series of deflection fields within the tube in the space intervening between the electron beam source and the target electrode. The relatively high frequency carrier current signals to be used in this case as voltages for controlling the plurality of deflecting fields are impressed upon one pair of terminals of a transmission line which preferably is terminated in such a manner that it is resonant. The transmission line is tapped at points located therealong at distances equal to a half a wave length of the radiant carrier frequency energy. The voltages developed at appropriate intervals at these tapped points of the transmission line thus are instantaneous maximum voltages of the energy impressed thereon for the reason that they are developed at simultaneously produced antinodal or loop points of the voltage wave propagated along the transmission line. By impressing the voltages developed at the tapped points along the transmission line in suitable polarity upon the respective field producing means, it is possible to produce corresponding deflection fields along the axis of the tube so that an electron beam traversing the succession of fields at a suitable rate is subjected to a series of corresponding deflecting influences, each of which increases the magnitude of the beam deflection by a predetermined small amount. The final result is that the beam emerges from the last of the fields with a deflection of considerable magnitude which is the aggregate of all of the individual deflections imparted thereto. The spacing of the means for producing the plurality of deflecting fields along the axis of the tube is related to the velocity of the electron beam in such a manner that the time required for the beam to travel from one field to another is substantially equal to a half a wave length of the high frequency deflecting voltage.

For a better understanding of the invention, together with other and further objects thereof, reference is had to the following description, taken in connection with the accompanying drawing, and its scope will be pointed out in the appended claims.

The single figure of the drawing shows schematically a cathode ray device and associated deflection control apparatus embodying the invention in the form of a single tube radiant energy receiver.

Having reference now to the drawing, the cathode ray device consists of an evacuated envelope or tube 1. Adjacent one end of the tube there is provided an electron emitter such as a thermionic cathode 2. The cathode may be heated for emission by any conventional means such as an indirect heater element 3 which may be connected to any convenient source of energy such as the illustrated battery 4. Adjacent the cathode 2 there also is provided an intensity control element such as a grid 5. The electrons are

accelerated initially and formed into a beam of the desired cross section by conventional means such as a beam forming accelerating electrode 6.

A pair of vertically disposed plates 7 are provided adjacent the path of the electron beam emerging from the electrode 6. The function of these plates is to suitably control the beam in a horizontal plane as viewed in the drawing. The voltage for producing the beam controlling field between the plates 7 may be derived from any convenient source such as a battery 8. In order to control the strength of the field produced between the plates 7 so as to properly locate the horizontal position of the beam, there is provided a potentiometer 9 connected in parallel with the battery.

Still farther along the path traveled by the electron beam there is located a plurality of horizontally disposed pairs of deflecting plates 10, 11, 12 and 13. Each of the respective pairs of plates 10 to 13 is located symmetrically relative to the central axis of the tube along which the undeflected electron beam would travel. Each pair of plates also is spaced from an adjacent pair of plates longitudinally along the axis of the tube by a predetermined amount dependent upon the velocity of the electron beam and the frequency of the deflection voltage to be employed.

Adjacent the right hand end of the tube 1 there is provided a target electrode 14 which embodies a centrally disposed small aperture 15 in such position, for example, that it lies on the path of the undeflected beam. Behind, or as viewed in the drawing to the right of, the target electrode there is mounted a multistage electron multiplier comprising a series arrangement of a plurality of secondary electron emissive electrodes such as 16 and 17. The first stage electrode 16 is mounted directly behind the aperture 15 so that its sensitized secondary electron emissive surface is impinged by electrons passing through the aperture. An electron collecting electrode 18 is located adjacent the last multiplier electrode 17.

With the exception of the beam deflecting plates, the electrodes of the tube and the electron multiplier have suitable fixed operating potentials impressed thereon which may be derived from any convenient source or plurality of sources of energy in accordance with well known practice. In the present instance the source of operating potentials for the tube is illustrated as a battery 19 provided with a plurality of taps so that the potentials impressed upon the various electrodes may be made to correspond suitably to one another. The cathode 2 of the electron gun for producing the beam of electrons is connected to the negative terminal of the battery 19. The control grid 5 is connected to a potentiometer 20 which is connected between the negative terminal and a somewhat more positive point of the battery, such as 21. In a similar manner the accelerating anode 6 is connected to a potentiometer 22 which is connected between the point 21 and a still more positive point 23 of the battery. The target electrode, which is electrically connected to the first multiplier electrode 16, and the rest of the multiplier electrodes are connected to points of the battery 19 which are increasingly more positive in accordance with conventional practice in devices of this character. The collector electrode 18 is connected through a load resistor 24 to the grounded positive terminal of the battery 19. The signal voltages developed in the output resistor are impressed upon any

desired utilization circuit 25 connected across the output resistor.

The signal-modulated high frequency carrier wave energy is intercepted by an antenna such as the dipole antenna 26 illustrated. The antenna 26 is coupled by condensers 27 to the two input terminals of a transmission line 28. This device may have any conventional electrical structure such as a coaxial cable, a Lecher wire system or the like. At suitable frequencies the transmission line may consist of a network of lumped circuit elements such as resistors, capacitors and inductors. In the case of a transmission line such as a coaxial cable, a Lecher wire system or the like, the line will have considerable length, for the reason that the velocity of the electron beam of the cathode ray device is only a fraction of the velocity of the wave propagation along the transmission line. In order to conserve space it is contemplated that such a transmission line may be coiled or otherwise formed in any desired manner. However, for the purpose of simplifying the instant illustration, a transmission line of the Lecher wire type is shown as two substantially parallel linear conductors. It will be understood that there is no intention of implying that the length of the transmission line 28 or any parts thereof necessarily bear a relationship to the spacing of the deflecting plates 10 to 13. These relationships depend, as will be apparent presently, upon the frequency of the deflection voltage and the velocity of the electron beam.

The invention embodying a transmission line for the impression of deflecting voltages upon the electrodes of the cathode ray device may be practiced by so terminating the transmission line that there will be produced either traveling waves or standing waves, as desired. Inasmuch as it is desired to develop maximum deflection voltages from relatively small quantities of received energy, it is preferred to terminate the transmission line in such a manner that there will be produced standing waves. In this manner the maximum deflection voltages may be developed. Consequently, in the preferred embodiment of the invention illustrated the right hand terminals of the transmission line, as viewed in the drawing, are connected to an impedance device having a value considerably different from the characteristic impedance of the line. In such a case the terminals of the transmission line 28 are interconnected through relatively high impedance devices such as resistors 29. These resistors are of the order of several thousands of ohms so that they differ materially from the characteristic impedance of the transmission line. Consequently, the energy which is propagated along the line from the antenna 26 to the other terminal is reflected from this terminal for propagation back toward the terminal coupled to the antenna. It will be obvious to those skilled in the art that standing waves alternatively may be produced either by short circuiting the line terminals or by leaving them open-circuited.

In this manner the transmission line is made resonant and there is produced along the line a standing wave which is substantially of the form illustrated by the broken line 30. At points 31, which are spaced from the input terminals of the transmission line by substantially a half a wave length, there are provided connections from the respective transmission line conductors to the first pair of vertical deflecting plates 10. Similarly, at points 32, which are spaced along the transmission line at a distance of a half a wave

length from the points 31, connections are made to the pair of deflecting plates 11. In this case, however, it is noted that these connections are reversed from those made to the plates 10. In like manner, the plates 12 are connected to the respective transmission line conductors at points 33, which are located a half a wave length distant from the points 32. The polarity of the connections to the plates 12 is the same as that for the plates 10 inasmuch as the respective transmission line connecting points 31 and 33 are separated by a distance equal substantially to one full wave length. Similarly, the deflecting plates 13 are connected, in like polarity to the plates 11, to points 34 on the transmission line conductors, which are removed from the points 33 at a distance of substantially a half a wave length. Obviously, as many pairs of deflecting plates and associated connections to a transmission line such as 28 may be provided as are required to effect the desired magnitude of beam deflection.

In order to secure stable operation of apparatus of the character described it is necessary to electrically correlate certain of the electrodes and auxiliary apparatus. Consequently, the focusing and accelerating electrode 6 is connected to one of the horizontal deflection plates 7 so that these two electrodes operate substantially at the same unidirectional voltage. For a similar reason the terminating resistors 29 for the transmission 28 may be connected to the accelerating electrode 6 as shown, or to a source of unidirectional energy of suitable voltage, whereby the terminating resistors and the accelerating anode are operated substantially at the same potential.

Referring now to the operation of the described apparatus, assume that the cathode 2 is conditioned by heating, as illustrated, or otherwise as desired to effect the emission of a copious quantity of electrons. A suitable number of the emitted electrons to form an electron beam of the intensity desired are permitted to pass through the intensity control grid 5 by suitably adjusting the rheostat 20. The electrons so passed are formed conventionally into a beam of the desired cross-sectional area by the electron optical conditions existing inside of and near the accelerating electrode 6. Also, the desired velocity or relative stiffness of the electron beam so formed is secured by an appropriate adjustment of the potential with respect to the cathode which is applied to the accelerating anode 6. This accelerating potential is subject to considerable variation by means of the potentiometer 22 for an adjustment purpose to be described presently. The beam is centered horizontally, or otherwise located as desired with respect to the aperture 15, under the control of the voltage impressed between the plates 7 which is susceptible of variation by means of the potentiometer 9. Once the horizontal location of the electron beam with respect to the aperture 15 is fixed, further adjustment of the potentiometer 9 ordinarily will not be necessary.

The relatively high frequency carrier wave energy which is modulated in amplitude in accordance with the intelligence signals is received by the dipole antenna 26, and as a result a relatively small voltage varying in amplitude in accordance with the modulated carrier wave is impressed upon the transmission line 28. Inasmuch as in the present instance the other terminals of this transmission line are connected to an impedance considerably greater than the characteristic impedance of the line, the energy which is prop-

agitated down the transmission line is substantially unabsorbed at the right hand end thereof as viewed in the drawing. Thus, this energy is reflected back along the transmission line in the direction of the input terminals. By proper selection of the length of the transmission in a manner well known in the art, the reflected energy is in phase with the input energy. As a consequence, there is produced along the transmission line a standing wave. At the points along the transmission line where antinodes of the standing wave occur, there are developed maximum voltage differences. As described, it is at these points that the deflecting plates 10 to 13 are connected.

Consider now the effect of the various deflecting fields produced by the plates 10 to 13 upon an electron beam traveling from left to right as viewed in the drawing between successive pairs of vertical deflecting plates. While a given portion of the electron beam is passing through the field produced between the first pair of deflecting plates 10, assume that the voltage impressed between these two plates is at an instantaneous maximum negative value as indicated at the point 31 by the broken line curves 30. The electrons comprising this portion of the beam, therefore, will be deflected from the straight line path between the anode 6 and the aperture 15 by a predetermined small amount, say in an upward direction as viewed in the drawing.

This group of electrons travels from the plates 10 to the plates 11 at a rate determined by the acceleration imparted thereto by the anode 6. By suitable design and control of the accelerating voltage the time required for the electron travel between plates 10 and 11 may be made substantially equal to the time required for the relatively high radio frequency voltage to vary through one half a cycle. Thus, when this group of electrons reaches the field of influence of the plates 11 the energy in the transmission line 28 will have reached a positive maximum instantaneous value such as indicated at the point 32. By impressing this transmission line voltage upon the deflection plates 11 in a polarity opposite to that of the plates 10, it is seen that the field produced between the plates 11 will be substantially of the same polarity and magnitude as the field produced a short time earlier between the plates 10. Therefore, the same portion of the electron beam is deflected again upwardly by a small predetermined amount.

The spacing between the pair of plates 12 and the pair of plates 11 and also that between the pairs of plates 13 and 12 is substantially the same as the spacing between the pairs of plates 11 and 10. For this reason the considered portion of the electron beam requires substantially the same time to travel between plates 11 and 12, and subsequently between plates 12 and 13, as the time required for this portion of the beam to travel between the pairs of plates 10 and 11. Then, by reason of the described connections of the plates 12 and 13 to the transmission line 28 at antinodal points of the standing wave, it is seen that the electron beam is successively deflected between the pairs of plates 12 and 13 by small predetermined amounts in both cases and in the same sense as the deflection thereof imparted by the pairs of plates 10 and 11. As a result, the beam emerging from the last pair of deflecting plates is displaced from the undeflected path of the electron beam by an amount substantially equal to four times that obtainable by the use of a single pair of deflecting elements. In this manner it is

obvious that it is possible to obtain a much greater deflection of the electron beam over the aperture 15. Hence, it is possible to increase the utility of a device of this character and at the same time to provide a device which is considerably easier to operate and control.

In the construction of a device of this character it is necessary only to space the deflecting plates 10 to 13 approximately, considering the velocity of the electron beam and to some extent the frequency of the deflecting voltages to be employed. It is, however, desirable that the spacing of the deflecting electrodes along the axis of the tube be as nearly uniform as possible so that, having made the necessary adjustments to effect the travel of a portion of the electron beam between the electrodes 10 and 11, for example, in substantially the same time required for the deflecting voltage to go through a half a cycle, the same adjustment will enable the arrival of the beam portion at the plates 12 and 13 at the times when the voltages impressed upon these pairs of plates are at their respective maximum values.

Hence, assuming a uniform spacing between the deflecting plates, in order to effect the necessary timing of the electron travel between successive pairs of deflecting plates it merely is necessary to adjust the voltage impressed upon the accelerating anode 6 by a suitable manipulation of the potentiometer 22. The greater the potential difference between the accelerating anode 6 and the cathode 2 the higher will be the velocity of the electron beam which is to traverse the fields created by the deflecting plates 10 to 13. It, therefore, is seen that this provides a relatively simple arrangement for adjusting a device of this character for a certain performance of the function for which it is intended.

While there has been described what, at present, is considered the preferred embodiment of the invention, it will be obvious to those skilled in the art that various changes and modifications may be made therein without departing from the invention, and therefore, it is aimed in the appended claims to cover all such changes and modifications as fall within the true spirit and scope of the invention.

What is claimed is:

1. An electron beam deflecting system for a cathode ray device comprising, a source of beam deflection energy, a plurality of deflecting field producing electrodes spaced along the path of said beam, and means including a transmission line connected at points spaced therealong to said electrodes for effectively connecting said energy source successively and in like polarity to said electrodes substantially coincidentally with the travel of said beam past the electrodes.

2. An electron beam deflecting system for a cathode ray device comprising, means energizable for producing two beam deflecting fields at points spaced along the path of said beam at distances such that a predetermined time is required for the beam to travel between said fields, an electrical structure of such character that electrical energy is propagated between two spaced points thereon in said predetermined time, means for impressing periodic electrical energy upon said electrical structure at a predetermined frequency, and means for deriving energy from said two spaced electrical structure points to energize in like polarity said two field producing means.

3. An electron beam deflecting system for a cathode ray device comprising, means for producing a plurality of beam deflecting fields at points

uniformly spaced along the path of said beam at distances such that a predetermined time is required for the beam to travel between two successive deflecting fields, an electrical structure of such character that electrical energy is propagated between successive ones of a plurality of uniformly spaced points thereon in said predetermined time, means for impressing periodic electrical energy upon said electrical structure at a radio frequency, and means for connecting said plurality of spaced electrical structure points respectively to said plurality of field producing means.

4. A system for deflecting an electron beam of a cathode ray device comprising, a plurality of deflecting electrodes uniformly spaced along the undeflected path of said beam, a transmission line, means for impressing upon said transmission line energy at a predetermined radio frequency, and means for connecting successive pairs of said electrodes to points on said transmission line spaced therealong at distances substantially equal to a half a wave length of said radio frequency energy.

5. A system for deflecting an electron beam of a cathode ray device comprising, a plurality of pairs of beam deflecting electrodes uniformly spaced along and symmetrically located relative to the axis of said device, a transmission line, means for impressing upon said transmission line alternating current energy of a predetermined frequency, means for connecting the successive pairs of said electrodes in opposite polarities to points of said transmission line spaced therealong at distances substantially equal to a half a wave length of said alternating current energy, and means for directing initially along the axis of said device an electron beam having an electron transit time between successive pairs of said deflecting electrodes corresponding substantially to the time of a half cycle of said alternating current energy.

6. Apparatus for deflecting the electron beam of a cathode ray device comprising, two pairs of deflecting electrodes mounted in said device in mutually spaced relationship and symmetrically located with respect to the axis of said device, a transmission line, means for impressing upon said transmission line alternating voltage having a predetermined frequency, means for connecting said pairs of deflecting electrodes to respective points on said transmission line spaced therealong to coincide with simultaneously developed antinodal portions of the alternating voltage propagated along said line, and means for directing an electron beam along the axis of said device at a velocity whereby the electron transit time between said two pairs of deflecting electrodes corresponds substantially to the time of a half cycle of said alternating current energy.

7. In a radiant energy receiving system, a cathode ray tube having two pairs of ray deflecting electrodes spaced along the axis of said tube, a radiant energy intercepting antenna, a transmission line connected to said antenna, connections between respective pairs of said deflecting electrodes and points on said transmission line spaced therealong at a distance substantially equal to a half a wavelength of said radiant energy, said two pairs of deflecting electrodes being connected in opposite polarity to said transmission line, and means for directing along the axis of said tube an electron beam having an electron transit time between said two pairs of

deflecting electrodes corresponding substantially to the time of a half cycle of said radiant energy.

8. In a radiant energy receiving system, a cathode ray tube having two pairs of ray deflecting electrodes spaced along the axis of said tube, a radiant energy intercepting antenna, a transmission line connected to said antenna, connections between respective pairs of said deflecting electrodes and points on said transmission line spaced therealong at a distance substantially equal to a wavelength of said radiant energy, said two pairs of deflecting electrodes being connected in the same polarity to said transmission line, and means for directing along the axis of said tube an electron beam having an electron transit time between said two pairs of deflecting electrodes corresponding substantially to the time of a full cycle of said radiant energy.

9. In a relatively high frequency radiant energy receiving system, a cathode ray tube having an electron gun for producing an electron beam and also having a plurality of pairs of beam reflecting plates uniformly spaced along the path of said electron beam, a radiant energy intercepting antenna, a transmission line connected to said antenna, connections between respective pairs of said reflecting plates and points on said transmission line spaced therealong at distances substantially equal to a half a wavelength of said radiant energy, and means for controlling said electron beam so that the electron transit time between successive pairs of said reflecting plates corresponds substantially to the time of a half cycle of said radiant energy.

10. In a relatively high frequency radiant energy receiving system, a cathode ray tube having an electron gun for producing an electron beam and also having a plurality of pairs of beam reflecting plates uniformly spaced along the path of said electron beam, a radiant energy intercepting antenna, a transmission line connected to said antenna, connections between respective pairs of said reflecting plates and points on said transmission line spaced therealong at distances substantially equal to a half a wavelength of said radiant energy, successive pairs of said plates being connected in opposite polarity to said transmission line, and means to impart to said electron beam a velocity such that the electron transit time between successive pairs of said reflecting plates corresponds substantially to the time of a half cycle of said radiant energy.

11. In a relatively high frequency radiant energy receiving system, a cathode ray tube having an electron gun including an accelerating electrode for producing an electron beam and also having a plurality of pairs of vertical beam deflecting plates uniformly spaced along the path of said electron beam, a radiant energy intercepting antenna, a resonant transmission line having one terminal connected to said antenna, connections between respective pairs of said deflecting plates and points on said transmission line spaced therealong at distances substantially equal to a half a wavelength of said radiant energy, successive pairs of said plates being connected in opposite polarity to said transmission line, and means including said electron accelerating anode to impart to said electron beam a velocity such that the electron transit time between successive pairs of said deflecting plates corresponds substantially to the time of a half cycle of said radiant energy.

12. In a relatively high frequency radiant en-

ergy receiving system, a cathode ray tube having an electron gun including an accelerating electrode for producing an electron beam, a target electrode having an aperture, a pair of horizontal beam deflecting plates and a plurality of pairs of vertical beam deflecting plates uniformly spaced along the path of said electron beam, a radiant energy intercepting antenna, a resonant transmission line having one terminal connected to said antenna, connections between respective pairs of said vertical deflecting plates and points on said transmission line spaced therealong at distances substantially equal to a half a wavelength of said radiant energy, successive pairs of said vertical deflecting plates being connected in opposite polarity to said transmission line, means for impressing upon said pair of horizontal deflecting plates a potential suitable to position said beam horizontally in alignment with said target electrode aperture, and means for impressing upon said electron accelerating anode a potential suitable to impart

5 to said electron beam a velocity such that the electron transit time between successive pairs of said vertical deflecting plates corresponds substantially to the time of a half cycle of said radiant energy.
